VULCANIZER

Thomas H. Williams, Akron, Ohio, assignor to
 National Rubber Machinery Company, Akron,
 Ohio, a corporation of Ohio

Application July 31, 1934, Serial No. 737,753

19 Claims. (Cl. 18—17)

This invention relates to vulcanizers of the individual, watchcase type such as may be used for vulcanizing inner tubes, small molded articles and the like, and more especially it relates to 5 vulcanizers of the character mentioned having means for opening and closing the vulcanizer, and means operating in timed relation thereto for locking the vulcanizer when closed.

In some of its aspects the invention is an improvement upon the vulcanizer of Michelson, Patent No. 2,000,406, issued May 7, 1935, wherein respective fluid pressure actuated cylinders, operating in timed relation to each other, are provided for opening and closing the vulcanizer, 15 and for operating the locking means when the vulcanizer is closed. Fluid pressure cylinders are inherently subject to non-uniformity of operation so that in providing for timed operation of two such cylinders it is necessary to make allowance for non-uniformity of operation, with the result that valuable time is wasted, especially where the operation of one cylinder immediately follows the operation of the other.

The chief objects of the invention are to provide 25 a rotary motor driven means for operating a vulcanizing press of the type having locking means located exteriorly of the vulcanizer; to provide means for opening and closing a vulcanizer and for locking the same, which means will be positive in operation so that they may follow 30 in close sequence, whereby saving of time is effected; and to provide vulcanizer-operating means of the character mentioned which may be stopped and reversed at any time during an operative cycle to avoid partly vulcanizing work that 35 may be improperly mounted in the vulcanizer.

Another important object of the invention is to provide vulcanizer-operating mechanism of the character mentioned that is absolutely safe 40 in that the vulcanizer when open cannot possibly close due to failure of the opening mechanism. A further object is to provide improved limit-switch construction whereby the operating motor is stopped automatically when the vulcanizer 45 reaches fully open or fully closed position. Other objects will be manifest.

Of the accompanying drawings,

Figure 1 is a side elevation of a vulcanizer embodying the invention, in its preferred form in 50 closed or operative position;

Figure 2 is a section, on a larger scale, on the line 2—2 of Figure 1;

Figure 3 is a fragmentary section, on a larger scale, on the line 3—3 of Figure 1;

55 Figure 4 is a detail side elevation of a portion of the apparatus shown in Figure 1, the cover of a switch-box being removed to show the mechanism therein;

Figure 5 is a view similar to Figure 4, showing 60 the position of the apparatus during the initial

phase of an opening operation, a part of the structure being broken away for clearness of illustration; and

Figure 6 is a view similar to Figure 4 showing the position of the parts when the vulcanizer is 5 in completely open position.

Referring to the drawings, the vulcanizer comprises a pair of spaced apart base members or standards 10, 10 upon which is mounted an annular bed or lower platen 11 that carries the 10 lower section 12 of a two-part mold comprising annular, mating, steam-jacketed mold sections 12, 13. The platen 11 is arranged at an angle to the standards 10 with its front at lower elevation to facilitate the mounting and removal of 15 work from the mold, and for removing water of condensation from the steam jackets thereof. The platen 11 is formed with an upstanding annular, axial flange 14 that engages the inner periphery of the lower mold section 12 to prevent 20 lateral movement of the latter.

The base 11 is formed in its top face with a concentric, annular chamber or recess 15 in which is mounted an annular diaphragm 16 of elastic rubber, and a metal plate 17 superposed on the 25 diaphragm, said plate and diaphragm being clamped together to form a fluid-tight seal at their inner and outer peripheries. Pressure fluid is supplied to the space between the plate and diaphragm through a pipe 18 extending to a suitable source of pressure fluid (not shown). A suitable spacing and insulating structure 20 of metal and asbestos is positioned between the bottom of mold section 12 and the top of platen 11, and radial ribs or strips 21 are secured to the 35 bottom of the said insulating structure and extend into recess 15 so as to be engaged by plate 17 when the latter rises due to distension of diaphragm 16 when fluid pressure is admitted through pipe 18. The insulating structure prevents heat from the mold sections from deleteriously affecting diaphragm 16. The arrangement is such that the lower mold section 12 has limited axial movement relatively of platen 11 with the result that when the vulcanizer is closed 45 and locked, admission of pressure fluid through pipe 18 will force the lower mold section upwardly, firmly into engagement with upper mold section 13 throughout their mating faces.

At the rear of the vulcanizer the standards 10 50 are extended upwardly as shown at 10^a, and in their uppermost portion is journaled a hinge pin 23 that is positioned substantially in the parting plane of the mold sections 12, 13. Between the standard-extensions 10^a the hinge pin 23 is 55 square as shown and carries a bifurcated hinge arm 24 that is formed with a pair of aligned slots, such as the slot 25, in which the hinge pin is received. Respective adjusting screws 26 extend through the hinge arm structure into slots 25 to 60

engage hinge pin 23, the arrangement being such that the hinge arm may be adjusted relatively of the hinge pin when molds of different heights are used in the vulcanizer. The construction 5 also permits the hinge arm to be lifted off the hinge pin, upon occasion, by upward movement of the mold sections induced by distension of the diaphragm 16. The hinge arm 24 extends forwardly from its pivot 23 and at its forward end is 10 removably connected to an upper platen or spider 27 by means of a pair of pins 28, 28. The upper mold section 13 is secured to the under side of upper platen 27 by screws 29, 29 or any other suitable means.

15 As is shown in Figure 2, the mold sections 12, 13 define an annular molding cavity 31 for the vulcanization of an annular, hollow article 32, such as an inner tube, but it will be understood that other molds may be provided for molding and 20 vulcanizing other articles, and they may be solid or hollow as desired.

The respective portions of the hinge arm 24 extend rearwardly of pivot pin 23 and at their rear ends carry respective pivot pins 34 by which they 25 are pivotally connected to the upper ends of respective arcuate links, such as the link 35. The said pivotal connection includes a slot 36 in each link 35 through which slot pivot pin 34 extends with the result that there is a determinate amount 30 of lost motion between hinge arm 24 and links 35. The lower ends of links 35 are positioned on opposite sides of a cam and crank gear 38 and are pivotally connected to the latter by a crank pin 39. The cam and crank gear 38 is mounted upon 35 a crank shaft 40 that is suitably journaled at its end portions in the respective standards 10. The gear teeth on the cam and crank gear extend about two-thirds the distance about its periphery, and mesh with a pinion 41 that is mounted upon a counter-shaft 42 that is journaled in the 40 respective standards 10. Mounted upon one end of counter-shaft 42 is a gear 43 that is meshed with the driving pinion 44 of a reduction gear device 45 that is associated with a reversible motor 46. The latter is provided with a magnetic brake 47 of known design.

Referring to Figures 4, 5, and 6, it will be seen that opening of the vulcanizer is effected by the 50 rotation of cam and crank gear 38, in a clockwise direction, from the position shown in Figure 4 to the position shown in Figure 6. Closing of the vulcanizer is effected by reverse rotation of the said gear through the same angular distance. The initial movement in clockwise direction of 55 gear 38, wherein it moves from the position shown in Figure 4 to the position shown in Figure 5, produces no corresponding movement of upper platen 27 because of the lost motion connection between link 35 and hinge arm 24, the 60 interval required for this movement being utilized for unlocking the vulcanizer as presently will be explained. When the vulcanizer is in the fully opened position shown in Figure 6, it will be observed that crank pin 39 is over-center with 65 relation to pivot pin 34 and crank shaft 40, with the result that the static weight of the upper platen 27 and mold section 13 urges the cam and crank gear 38 to rotation in a clockwise direction. Thus if there should be any failure or 70 breakage of the motor-brake or reduction gear mechanism, while the vulcanizer is open, clockwise rotation of gear 38 would carry link 35 to a positive stop against crank shaft 40, thus preventing descent of the upper platen and mold sec-

tion. The arrangement makes for increased safety to the operator.

For locking the vulcanizer in closed position during vulcanizing operations, a pair of laterally disposed locking arms 50, 50 are provided, said locking arms being centrally pivoted at 51, 51 in suitable respective brackets 52 formed on the lower platen 11 at opposite sides thereof. Each locking arm 50 is of open, truss-like construction in that portion thereof above its pivot, and has 5 its upper end forked, there being a pin or shaft 53 journaled in said fork. The medial portion of shaft 53 is eccentric with relation to the journals thereof, and clamped upon said eccentric portion is a wedge block 54 that has an oblique 10 bottom face. A pin or stud 55 mounted in one side of the locking-arm fork extends between the clamp flanges of the wedge block 54 in such a manner as to permit limited angular movement of the latter and its supporting shaft 53. The 15 upper platen 27 is formed with heavy, bracket-like lugs 56, 56 projecting laterally from opposite sides thereof, the top faces of said lugs being somewhat tapered or downwardly sloped. The oblique, bottom faces of the respective wedge 20 block 54 engage the complementally sloped faces of the lugs 56 with a wedging action in the closed or locked condition of the vulcanizer, as shown in full lines in Figure 2, the pivotal mounting of the shafts 53, which permits limited angular 25 movement of the wedge blocks 54, enabling the latter to seat flush on the lugs 56 under all conditions. Rotation of shaft 53 will alter the position of wedge block 54 lengthwise of locking arm 30 whereby the effective length of the latter may 35 be varied to suit variable conditions.

The locking arms 50 are moved between the locking position shown in full lines in Figure 2 and the unlocked position shown in broken lines in the same figure by power mechanism that 40 engages the lower ends of said locking arms. As is most clearly shown in Figures 1 and 3, the lower portions of the locking arms 50 are of lesser width than those portions thereof above pivots 51, and are not transversely aligned with each 45 other, being on opposite sides of the plane indicated by section line 2—2 of Figure 1 of the drawings. Pivotedly mounted on pivot pins 58 in the free lower ends of the respective locking arms 50 are blocks 59, 59 disposed on each side of said 50 arms. Each block 59 is formed with an aperture above and below its pivot 58 in which apertures are slidingly received one end of respective connecting rods 60, the other ends of the latter being fixedly secured to blocks 61, 61 that are similar 55 to blocks 59 and are pivotally mounted at their middles upon hinge pins 62 mounted in one end of respective racks 63. Respective compression springs 64 are mounted upon the connecting rods 60 between blocks 59, 61, and nuts 65 threaded 60 onto the ends of said rods and bearing against blocks 59 are provided for adjusting the position of the locking arms 50 with relation to racks 63. The arrangement is such as to provide yielding connections between the racks 63 and the locking arms whereby no damage will result if the wedge blocks 54 do not pass freely into engagement with the sloped faces of lugs 56 during the 65 operation of locking the vulcanizer.

The racks 63 mesh with a pinion 67, on opposite sides thereof, said pinion being journaled on a stub-shaft 68 that extends downwardly from the bottom of lower platen 11, at the axis thereof. The pinion 67 is enclosed in a housing 69 that is carried by lower platen 11, and said housing 75

carries a pair of rollers 70, 70 that engage the backs of respective racks 63 for holding the racks in mesh with pinion 67. Housing 69 also is formed with a slideway for a rack 72 that is 5 meshed with pinion 67, said rack 72 being disposed transversely of racks 63 in a different plane, and extending toward the rear of the vulcanizer. At its rear end the rack 72 is secured to a slide 73 that straddles and is supported by a square 10 guide block 74 that is journaled upon crank shaft 40, the slide being movable longitudinally relatively of said guide block. A collar 75 on the crank shaft holds the guide block 74 in place adjacent the hub of gear 38, the latter and said 15 collar preventing movement of the slide laterally of the guide block. Longitudinal reciprocation of slide 73 is effected by means of a roller cam-follower 76 that is journaled on a spindle 77 that is mounted in slide 73 and projects toward cam 20 and crank gear 38, said cam-follower engaging in an arcuate cam groove 78 formed in said gear. Reciprocation of slide 73 reciprocates rack 72 and thereby oscillates pinion 67 to reciprocate racks 63 in opposite directions whereby angular movement 25 of locking arms 50 is effected for locking and unlocking the vulcanizer.

As will be seen from the drawings, the major portion of cam groove 78 is disposed adjacent the outer perimeter of the cam and crank gear and 30 is concentric with crank shaft 40. A minor portion of the cam groove, at one end thereof, turns sharply inward and terminates close to the hub of the gear. The crank pin 39 and cam groove 78 are so disposed relatively of each other that 35 when the vulcanizer is in the closed position shown in Figure 4, cam-follower 76 is at the innermost part of cam groove 78 whereby the locking arms 50 are in the locking position shown most clearly in full lines in Figure 2. When the 40 cam and crank gear is in the position shown in Figure 5, in which position the link 35 is ready to start the lifting of the upper platen and upper mold section, cam-follower 76 has almost reached the concentric portion of cam groove 78, and the 45 locking arms 50 have been swung angularly, as shown in broken lines in Figure 2, sufficiently clear of lugs 54 of the upper platen to permit the latter to be lifted. The cam-follower rides in the concentric portion of cam groove 78 as gear 38 moves from the position shown in Figure 5 to the position shown in Figure 6 to lift the upper platen 27 and thus holds the locking arms 50 in spread apart, inoperative position.

Sometimes the mold sections 12, 13 stick to each 55 other during a vulcanizing operation so that lifting of the upper mold section exerts a strong upward pull on the lower mold section. To prevent such pull from lifting the lower mold section off its centering flange 14, a safety device 60 is provided, said device comprising a block 80 that is mounted for angular adjustment upon the front of lower platen 11, and an angular arm 81 that is mounted for longitudinal adjustment upon block 80. The upper end portion of arm 81 is 65 rearwardly inclined, and an adjustable stop-stud 82 is threaded therethrough, the operative end of said stop-stud being disposed adjacent but not in contact with the base flange of lower mold section 12. The arrangement is such that stud 82 permits such upward movement of the lower mold 70 section as is induced by the distension of diaphragm 16, but prevents further upward movement of the mold section such as might be caused by sticking to the upper mold section. The feature of angular and longitudinal adjustability of

block 80 and arm 81, respectively, adapt the device for use with mold sections having base flanges of different sizes and heights.

Sometimes it is important that the mold sections 12, 13 be positioned and retained in determinate angular relation to each other. To this end the brackets 52 on one side of the vulcanizer are extended upwardly in the form of ears 52a, 52a through which are threaded respective adjusting screws 84, 84 that engage opposite sides of one 10 of the lifting lugs 85 that project from opposite sides of the mold section 12. The lug 85 may be grooved, as shown in Figure 1, to receive the ends of said adjusting screws, and the latter are not set up too tightly as to interfere with 15 such upward movement of the mold section as is induced by distension of diaphragm 16. The screws 84 retain the lower mold section 12 in proper angular position and provide means for limited angular adjustment of the mold section. 20

The apparatus is electrically operated, preferably by means that is substantially automatic in its operation so that after the work is mounted in the vulcanizer, the pressing of a single button will start a cycle of operation that terminates 25 with the opening of the apparatus to permit the removal of the full vulcanized article. The electric control means includes manually operated means whereby the cycle of operation may be interrupted at any time and the vulcanizer again 30 opened, and when inflatable articles are vulcanized in the apparatus the control means may also control the admission of pressure fluid to the article and the venting of fluid therefrom. Admission of pressure fluid through pipe 18 to 35 distend diaphragm 16 also is automatically effected. Electric control mechanism of the character mentioned is well known to trade and for that reason is not shown herein except for an improved limit switch which serves to cut off the 40 operation of motor 46 and apply magnetic brake 47 thereto when, in the operation of the apparatus, the movable upper platen reaches its fully open or fully closed position.

The said limit switch is enclosed in a housing 87 45 that is formed integral with one of the standards 10, about the journal of crank shaft 40, and provided with the usual cover. The end portion of crank shaft 40, reduced in diameter, extends into housing 87, and mounted upon said end portion 50 of the crank shaft are two switch levers 88 and 89 and a switch bracket 90, the latter being journaled on the shaft between the switch levers 88, 89 which are secured to the shaft. The free end portions of switch levers 88, 89 are bent at right 55 angles so as to project into the plane of the switch bracket 90 as is most clearly shown in Figure 3. The switch bracket 90 comprises a downwardly extending plate upon which are mounted two make-and-break switches 91, 92 disposed at an 60 angle to each other in the orbits of the overhanging end portions of the switch levers 88, 89. A pair of tension springs 93, 93 are connected to two spaced points on the switch bracket 90 and to an adjustable stud 94 threaded through 65 the bottom of housing 87, the arrangement being such as yieldingly to hold the switch bracket in determinate angular position on crank shaft 40. Each switch 91, 92 is provided with a depressible 70 operating button 95.

It will be seen with reference to Figure 4 that when the vulcanizer is fully closed switch lever 88 is in engagement with switch 91, holding the same in reverse condition whereby power is disconnected from motor 46 and applied to magnetic brake 75

47. In like manner, when the vulcanizer is fully open switch lever 89 is in engagement with switch 92, as shown in Figure 6, to hold said switch 92 in reverse condition whereby motor 46 is idle and brake 47 is applied thereto. In either case it will be seen that switch bracket 90 has been tilted out of normal position against the tension of one of the springs 93. The arrangement is such as to allow for coasting or over-run of the cam shaft 40 between the time switches 91 or 92 are operated and the time that motor 46 is brought to a complete stop. The switch arms 88, 89 are adjustable angularly on cam-shaft 40 so that the opening and closing movements of the vulcanizer may be stopped at the proper instant while allowing for the over-run mentioned.

10 The electrical control means also includes a switch box 97, Figure 1, that is mounted at the front of the vulcanizer for the convenience of 20 the operator, said switch box enclosing three push-button switches marked "raise", "lower", and "stop". These switches are so mounted in the electric control circuit as to permit the operator to stop the operation of the vulcanizer at 25 any time during an operative cycle and to raise and/or lower the movable platen as desired.

30 The operation of the vulcanizer is simple. With the vulcanizer in the open position shown in Figure 6, the work 32 is mounted in the mold cavity 31, and if the work is an inflatable article such as an inner tube, a fluid pressure connection (not shown) is attached to the inflating stem thereof. The operator then presses the "lower" button of switch 97 which starts an automatically controlled operative cycle comprising 35 lowering upper platen 27, locking upper platen by means of locking arms 50, admitting fluid to the work, and admitting fluid through pipe 18 to distend diaphragm 16. This condition of the 40 apparatus obtains for a determinate interval of time, sufficient to vulcanize the work, it being understood that the mold sections 12, 13 are constantly heated by the circulation of steam through their steam jackets. Automatically at 45 the termination of the vulcanizing interval, pressure fluid is vented from the work, pressure fluid is vented from pipe 18 to cause collapse of distended diaphragm 16, locking arms 50 are moved to unlocked position, and the upper platen is 50 raised to its open position. The finished work may then be removed, and the cycle repeated as often as desired.

55 The feature of providing the rotatable gear 38, which constitutes a crank, for opening and closing the vulcanizer, makes it possible to impart movement to the movable platen relatively slowly and to terminate said movement relatively slowly as compared to the rate of movement during the intermediate interval with the result 60 that jolts and jars largely are eliminated. The feature of forming a cam on the said gear and utilizing said cam for controlling the locking mechanism provides such positive and accurate timed operation of the locking mechanism with 65 relation to the opening and closing of the vulcanizer that one operation may closely follow the other without loss of time. The improved limit switch construction permits automatic stopping of the opening and closing movements of the 70 vulcanizer while taking advantage of over-run of the cam shaft to cushion the stop so as to avoid jolts and jars. The improved vulcanizer construction includes safety means which positively prevents lowering of the upper platen until it is 75 intentionally lowered, and it accomplishes the

other objects set out in the foregoing statement of objects.

Modification may be resorted to without departing from the spirit of the invention or the scope of the appended claims. 5

What is claimed is:

1. In a vulcanizer, the combination of a pair of relatively movable vulcanizer sections, an ar- 10 cuate, movable link pivotally connected at one of its ends to one of said vulcanizer sections, at least, for opening and closing the vulcanizer, an oscillatable crank to which the other end of said link is connected for imparting orbital movement to that end of the link, and a crank shaft on which the crank is mounted and which extends 15 across the path of movement of the link to limit the movement thereof in one direction when the vulcanizer is open.

2. In a vulcanizer, the combination of a pair of relatively movable vulcanizer sections, an ar- 20 cuate link connected at least to one of said sections for effecting relative movement thereof, a crank to which said link is connected, a crank-shaft carrying said crank, said crank-shaft traversing the path of movement of said link and 25 limiting the movement thereof in one direction when the vulcanizer is open, means for angularly moving said crank to actuate said link to open and close the vulcanizer, and means for stopping the movement of the crank in determin- 30 ate position such that when the vulcanizer is open the connection between the crank and link is over center with relation to the axis of the crank shaft and the connection of the link with the vulcanizer section, whereby retrogressive 35 movement of the link is prevented except upon angular movement of the crank.

3. In a vulcanizer, the combination of a sta- 40 tionary and a movable vulcanizer section, a link connected to the movable section for opening and closing the vulcanizer, a crank to which said link is connected, said crank comprising a gear segment, a crank-shaft on which said crank is mounted, a reversible motor for oscillating said crank by means of said gear segment to open 45 and close the vulcanizer, and a pair of limit switches carried by the crank shaft for stopping rotation of the motor at determinate angular positions of the crank shaft.

4. In a vulcanizer, the combination of a sta- 50 tionary and a movable vulcanizer section, a link connected to the movable section for opening and closing the vulcanizer, a crank to which said link is connected, a crank-shaft supporting said 55 crank, a reversible motor for oscillating said crank and crank-shaft, a pair of yieldingly mounted limit switches for stopping rotation of the motor, and a pair of switch levers secured to said crank-shaft for engaging and operating said limit switches in determinate angular posi- 60 tions of the crank shaft.

5. In a vulcanizer the combination of a pair of relatively movable mold sections, a link connected to one of said sections for opening and closing the vulcanizer, a crank to which said link 65 is connected, a crank-shaft supporting said crank, a reversible motor for operating said crank and crank-shaft, a pair of limit switches swiveled on the crank-shaft, said switches being adapted to stop operation of said motor, and a 70 pair of switch levers secured on said crank-shaft for engaging and operating the respective limit switches in determinate angular positions of the crank shaft.

6. A combination as defined in claim 5 includ- 75

ing yielding means normally holding the limit switches in determinate angular position on the crank-shaft, yet permitting angular displacement of the switches upon engagement by the switch levers.

5. In a vulcanizer, the combination of a pair of relatively movable vulcanizer sections, a link connected to one of said sections for opening and closing the vulcanizer, a crank to which said link is connected, an angularly movable locking arm on one vulcanizer section adapted to engage the other section to lock the vulcanizer in the closed position thereof, cam means for operating the locking arm, and rotary power driven means 10 for turning the crank and cam in unison.

6. In a vulcanizer, the combination of a pair of relatively movable vulcanizer sections, a link connected to one of said sections for opening and closing the vulcanizer, an angularly movable locking arm on one vulcanizer section adapted to engage the other section to lock the vulcanizer in the closed position thereof, a unitary crank and cam structure having operative connection with the link and locking arm respectively, and 20 rotary power driven means for oscillating the crank and cam structure.

7. In a vulcanizer, the combination of a pair of relatively movable vulcanizer sections, a link connected to one of said sections for opening and closing the vulcanizer, an angularly movable locking arm on one vulcanizer section adapted to engage the other section to lock the vulcanizer in the closed position thereof, a single, angularly movable, driven member to which said 30 link and locking arm are connected to operate the same in timed relation to each other, and a reversible electric motor for oscillating said last mentioned member.

8. In a vulcanizer, the combination of a pair of relatively movable vulcanizer sections, a link connected to one of said sections for opening and closing the vulcanizer, an angularly movable locking arm pivoted on one vulcanizer section adapted to engage the other section to lock the vulcanizer in the closed position thereof, a unitary cam and crank structure having connection with the locking arm and link, the latter connection being a lost motion connection for operating the locking arm and link in timed relation 40 to each other, and rotary power driven means for oscillating the cam and crank structure.

9. A combination as defined in claim 10 including a yielding connection between the locking arm and the cam and crank structure.

10. In a vulcanizer, the combination of a pair of relatively movable vulcanizer sections, a link connected to one of said sections for opening and closing the vulcanizer, a locking arm pivoted to one vulcanizer section and engageable with the other vulcanizer section for locking the vulcanizer in the closed position thereof, a rack connected to one end of said locking arm, a pinion with which said rack is meshed, a second rack meshed with said pinion for driving the same, and a single power member for reciprocating said second rack and link.

11. In a vulcanizer, the combination of a pair of relatively movable vulcanizer sections, a link connected to one of said sections for opening and closing the vulcanizer, a pivotally mounted locking arm adapted to engage a vulcanizer section to lock the vulcanizer in the closed position thereof, a rack connected to one end of said locking arm, a pinion with which said rack is meshed, a second rack meshed with said pinion for driving the same, and a reversible motor for operating the crank and cam in unison.

12. In a vulcanizer, the combination of a pair of relatively movable vulcanizer sections, a link connected to one of said sections for opening and closing the vulcanizer, a crank to which one end of said link is connected, a pivotally mounted locking arm adapted to engage a vulcanizer section to lock the vulcanizer in the closed position thereof, a rack connected to one end of said locking arm, a pinion with which said rack is meshed, a second rack meshed with said pinion for driving the same, and a reversible motor for operating the crank and cam in unison.

13. A combination as defined in claim 12 including a lost motion connection between the link and the rotary power driven member.

14. A combination as defined in claim 13 including a yielding connection between the locking arm and the rotary power driven member.

15. A combination as defined in claim 13 including a yielding connection between the locking arm and the rotary power driven member.

16. In a vulcanizer, the combination of a pair of relatively movable vulcanizer sections, a link connected to one of said sections for opening and closing the vulcanizer, a crank to which one end of said link is connected, a pivotally mounted locking arm adapted to engage a vulcanizer section to lock the vulcanizer in the closed position thereof, a rack connected to one end of said locking arm, a pinion with which said rack is meshed, a second rack meshed with said pinion for driving the same, a cam adapted to reciprocate said second rack, and a single rotary power member for operating said cam and crank in unison.

17. In a vulcanizer, the combination of a pair of vulcanizer sections, a link connected to one of said sections for opening and closing the vulcanizer, a pair of pivotally mounted locking arms on opposite sides of the vulcanizer adapted to engage a vulcanizer section to lock the vulcanizer in the closed position thereof, a pair of racks yieldingly connected to said locking arms, a pinion with which said racks are meshed, a second rack meshed with said pinion for driving the same, and means for reciprocating said link and second rack in timed relation to each other.

18. In a vulcanizer, the combination of a pair of vulcanizer sections, a link connected to one of said sections for opening and closing the vulcanizer, a crank with which one end of said link has lost motion connection, a pair of pivotally mounted locking arms on opposite sides of the vulcanizer adapted to engage a vulcanizer section to lock the vulcanizer in the closed position thereof, a pair of racks having yielding connection with said locking arms, a pinion with which said racks are meshed, a second rack meshed with said pinion for driving the same, a cam formed integral with said crank for reciprocating said second rack, and rotary power driven means for oscillating said crank.

19. In a vulcanizer, the combination of a pair of vulcanizer sections, a link connected to one of said sections for opening and closing the vulcanizer, a crank with which one end of said link has lost motion connection, a crank-shaft supporting said crank, a pair of pivotally mounted locking arms on opposite sides of the vulcanizer adapted to engage a vulcanizer section to lock the vulcanizer in the closed position thereof, a pair of racks having yielding connection with the said locking arms, a pinion with which said racks are meshed, a second rack meshed with said pinion for driving the same, a cam formed integral with said crank for reciprocating said second rack, and rotary power driven means for oscillating said crank.

20. In a vulcanizer, the combination of a pair of vulcanizer sections, a link connected to one of said sections for opening and closing the vulcanizer, a pivotally mounted locking arm adapted to engage a vulcanizer section to lock the vulcanizer in the closed position thereof, a rack connected to one end of said locking arm, a pinion with which said rack is meshed, a second rack meshed with said pinion for driving the same, a cam formed integral with said crank for reciprocating said second rack, a reversible motor for rotating said crank and crank shaft, and a pair of limit switches carried upon the crank shaft for stopping the reversible motor in determinate angular positions of the crank.

THOMAS H. WILLIAMS.
